LARGE SIZE VERTICAL FILING MEANS

Harold L. De Lisle, Two Rivers, Wis.

Application January 2, 1937, Serial No. 118,729

5 Claims. (Cl. 45—7)

This invention relates to large size vertical filing means more particularly for drafting room equipment and the filing in vertical, unfolded position of drawings, tracings, prints, and the like.

Heretofore, these have been filed in open-top boxes, with or without covers. Since the average drawing, tracing or print filed in this manner is about twenty-four inches by thirty-six inches and the file, when loaded, weighs frequently as much as five hundred pounds, it will be appreciated that such boxes take up considerable floor space and cannot be readily moved around. For the reason that the tops of the boxes must remain accessible, the boxes must remain on the floor of the office or drafting room, the space thereabove being wasted.

Conservation of floor space is becoming more and more of a factor of importance and this heretofore known method is becoming increasingly costly, as well as subjecting the files to dust, and fire and water hazard, since even if a cover is provided for the box, the inconvenience of raising and lowering it encourages the leaving of the file exposed, at least for the greater part of the day.

The present invention aims to provide means for housing the vertical file in the form of a drawer in a casing, while still permitting ready accessibility and affording utilization of the space on the top surface or above the casing, for other purposes, and particularly active purposes such as other current files of various kinds.

The invention includes means for power operation of the drawer desirably by fluid under pressure such as compressed air, while also permitting hand operation should the compressed air be temporarily unavailable, or for other reasons. Thus the drawer may conveniently be kept normally closed when not in use. By means of the present invention, it has been found that the sheet capacity per foot of floor space has been increased substantially, and the floor cost rental per sheet materially reduced, in addition to the many other advantages enjoyed.

The invention will be understood by reference to the accompanying drawings showing an illustrative embodiment, in which—

Figure 1 is a perspective view showing a comparison between an old style file and the present invention;

Figure 2 is an enlarged front elevation of the structure of the present invention;

Figure 3 is a longitudinal section of the structure of Fig. 1 taken on the line 3—3 of Fig. 2,

showing in broken lines the drawer partially open;

Figure 4 is a view somewhat similar to Fig. 3 but looking in the opposite direction along the line 4—4 of Fig. 2;

Figure 5 is an enlarged detail, partially in section along the line 5—5 of Fig. 2;

Figure 6 is a sectional detail view of the control valve, taken on the line 6—6 of Fig. 8;

Figure 7 is a section on the line 7—7 of Fig. 6; 10 and

Figure 8 is a perspective view, somewhat diagrammatic, of the air system in separated relation.

Referring in detail to the drawings, I have 15 shown at 13 and 14 two filing units made in accordance with the present invention. It will be readily seen that the space above the old style filing box must be left accessible and is therefore of no further use for filing or storage space, 20 while the space above the units 13 and 14, in accordance with the present invention, may be utilized for the additional filing facilities represented by the group of filing cabinets 15 and 16, each respectively disposed above the units 13 25 and 14.

In this instance, the base for each of the group of filing cabinets 15 and 16 is constituted by the casing 17, one of the units of the present invention. In the unit 13, the drawer 18 is shown 30 partially withdrawn from the casing, that is, open, and in the unit 14 the drawer is shown retracted into the casing, that is, closed. It will be understood that the casing 17 rests directly on the floor of the office or drafting room and 35 for protection to the floor, while at the same time facilitating movement of the drawers into and out of the casing; the pair of tracks 19 are desirably extended from the casing 17 and also rest on the floor. These tracks may be merely 40 flat elongated steel plates of a thickness substantially the same as the bottom 20 of the casing which, together with the drawer, is advantageously made of pressed steel and has the side walls 21, top wall 22 and rear wall 23, the front 45 of the casing being open for the reception of the drawer.

The drawer 18 is a similar but smaller rectangular construction having a bottom 24, side walls 25, rear wall 26 and front wall 27, the latter being 50 preferably of double construction for additional strength. The top of the drawer is of course open for accessibility to its interior. For purposes of the present invention, the drawer is of materially less vertical height than the casing, leaving a 55

space 28 between the bottom of the drawer and the bottom of the casing, which space is occupied by antifriction means through the intermediation of which the drawer is movably supported in the casing. A dependent portion 29 for the front wall of the drawer may at least partially conceal the roller mechanism next described.

Extending from front to rear, underneath the drawer and affixed thereto, adjacent each side thereof are the runners 30, which are conveniently of irregular channel formation and upon which the drawer rests through the intermediation of transverse channel reinforcements 31. To provide an integral structure, the channels 31 may 15 be welded to the bottom 24 of the drawer running from side to side thereof and spaced apart from front to rear of the drawer, and the channeled runners 30 welded cross-wise to the channels 31. For this purpose, these channeled parts have 20 horizontally extending flanges 32, one each of which along the outer edge of the drawer as at 33 is extended to round the lower side corner of the drawer where it may be welded for further security.

25 In the present embodiment, a roller truck 34 extends beneath each of the runners 30 and supports the runners 30 (and thus the drawer) on the rollers 35 which may be secured in pairs on axles 36 journaled in the side walls of the truck 34. Rollers 35 are therefore in direct frictional contact with the runners 30 and the bottom 20 of the casing. To maintain the truck in lateral position, while permitting it to move relatively to the drawer and casing, each runner 30 may have 35 secured along its bottom an inverted channel member 37 which receives with a snug sliding fit a keeper bar 38 secured longitudinally along the upper face of the truck 34. Similarly, along the floor of the casing is a channel member 39 which is slidingly embraced by the sides of the truck, the truck itself being again of inverted channel formation.

On their inner faces the runners 30 are desirably offset as at 40 to provide a rest surface for 45 the yoke 41 fixedly secured to the runner and on which is axled a roller wheel 42 of somewhat larger diameter than the rollers 35. Thus as the drawer is withdrawn from the casing, the rollers 35 which are thus of the so-called progressive 50 type, will partially follow the outward movement of the drawer on the tracks 19, moving about half of the distance traveled by the drawer but sufficiently to afford adequate support for the drawer in its outermost open position. Further 55 support for the drawer in this position is also provided by the roller wheels 42, which move outwardly the same distance as the drawer since they are on an axis fixed with respect to the drawer. Upon retraction of the drawer to close it, the 60 rollers 35 will move correspondingly inwardly back to their original position. So that the entire roller support will be offset somewhat rearwardly of the drawer, it desirably terminates as at 43 short of the front wall 27 of the drawer but may 65 extend as at 44 beyond the rear wall 26. Thus the rollers are clear of the feet of the operator, for example.

I will now describe a preferred form of power mechanism for operating the drawer. Mounted 70 centrally along the bottom of the casing between the runners 30 is fixed an air cylinder 46 which may be supported by pedestal members 45 and 45a secured to the casing, and to which the cylinder is secured as by bolt straps 47 and 47a. Within the cylinder 46 is a piston 48 which is in-

clusive of the piston rod 49 of sufficient length to extend through the cylinder 46 at its forward end, when the piston 48 is almost at the rear end of the cylinder. At its forward end, the piston rod 49 is anchored to the depending front wall 29 of the drawer as by a nut 50 and cap nut 50a. At the forward end of the cylinder the cylinder head 51 accommodates the packing gland 52 through which the piston rod 49 moves. An internal shoulder 51a on the cylinder head may limit outward movement of the piston and therefore the drawer 18 in the casing. At this forward end also, the cylinder head 51 connects with the cylinder, through a nipple 53, the air pipe 54 which communicates with one branch 55 of a four-way 15 valve 56. At its rear end, the cylinder head 57 connects with the cylinder, through a nipple 58, an air pipe 59 which communicates with the branch 60 of the valve 56. A third branch 61 of the valve is in communication, by means of 20 the pipes 62 and 63, with a supply of air under pressure which may be provided by any conventional means not here necessary to be described. Still a fourth branch 64 of the valve provides an adjustable escapement for the air. As here 25 shown this includes a needle relief valve shown in detail in Fig. 7. For example, passage for the escaping air through the ports 65, 66 is controlled by the screw needle 67 which in turn may be manually controlled by the rod 68 integral 30 therewith and extending to the front face of the casing as at 69, where it may terminate in the screw head which may be adjusted as desired. Similarly, an air supply valve 70, between the pipes 63 and 62, may be controlled by a rod 71 35 terminating at the outer face of the casing as at 72 and similarly adjustable.

The four-way valve 56 is shown in detailed cross-section in Fig. 6 and the valve proper, as is well known with respect to mechanisms of this 40 type, includes a plug cylinder 73 through which pass the non-communicating ducts 74, 75. Upon rotation of the plug cylinder 73, the duct 74 is adapted to place in communication either the ports 76 and 77 for the pipes 62 and 59 respectively, or the ports 76 and 78 for the pipes 62 and 54 respectively. Similarly the duct 75 is adapted to place in communication either the ports 78, 79 for the pipe 54 and escape port 65 respectively, or the ports 77, 79 for the pipe 59 and escape port 50 65 respectively.

For operating the plug cylinder 73, it may have fixed thereto a hollow control member 80 of non-circular formation, here shown square, to receive the square rod 81 telescopically but 55 with a sliding fit. The rod 81 is fixed to a valve lever 82 carried on the right-hand upper corner of the front wall 27 of the drawer 18. By means of this telescopic arrangement, the valve lever 82 is always operatively connected with the plug 60 cylinder 73 whether the drawer be in its innermost or outermost positions, the telescoping interengagement of the member 80 and rod 81 being of sufficient extent to accommodate any normal movement of the drawer. The valve 56 65 and its associated pipes is conveniently supported by an L-shape bracket 83 secured to the rear wall 23 of the casing in alignment with the valve lever 82 on the drawer.

The operation of the device is as follows: 70

When it is desired to open the drawer, the valve lever 82 is moved downwardly from the position shown on the closed drawer in Fig. 1 to that shown on the open drawer. This places the pipes 62 and 59 in communication so that the 75

air forces the piston 48 outwardly, and, moving with it, the drawer 18. At this time the pipe 54 and escape port 65 are in communication and the air at the forward end of the cylinder escapes past the needle valve 67. By regulating this needle valve, the movement of the drawer may be made more or less rapid, and at the same time an air cushion is provided which progressively slows the drawer down as it approaches the end 10 of its outer movement as limited by movement of the piston 48 in the cylinder when it contacts the shoulder 51a or some other suitable stop means. Even when the piston reaches the end of its forward movement, however, and continuously until reversal of the valve lever 82, the piston is desirably under pressure so that the drawer has no tendency to roll back until so actuated by the operator.

When it is desired to close the drawer the 20 valve lever is moved upwardly again, placing the pipes 62 and 54 in communication so that the piston is retracted, drawing with it the drawer. At this time also, the pipe 59 and escape port 65 are in communication so that a similar air 25 cushion is provided on the return movement of the drawer.

Should the air supply fail for any reason, it is of course desirable to be able to open the drawers by hand and for this purpose I have shown a 30 heavy bail-like handle 84 extending nearly the entire width of the drawer so that it may be conveniently grasped by say two persons whose combined strength may be necessary to move the drawer by hand. In this operation, it may be 35 desirable, in order to avoid the air cushion already referred to and permit easier hand operation, to move the valve lever 82 to just the opposite respective positions which would be used for compressed air operation of the drawer. Thus it 40 will be seen that by placing the pipes 62 and 54 in communication when hand operation is resorted to, an air cushion at the forward end of the cylinder will be avoided. Again upon closing the drawer by hand, by placing the pipes 45 59 and 62 in communication an air cushion at the rear end of the cylinder will be avoided.

The handle 84 is desirably swingingly mounted on the front wall 27 of the drawer and in this instance its ends each are received between a 50 bifurcated bracket 86, the bifurcations of which have vertical elongated slots 87, a pair of trunnions 88 on the handle playing in these slots. When the handle is not in use, by this last mentioned connection it may be not only swung upwardly toward the face of the drawer but also 55 may be moved rectilinearly upwardly a sufficient distance to pass onto the hooks 89 carried along the upper edge of the drawer where it will remain until removed by first being lifted rectilinearly upwardly and then swuny forwardly and downwardly.

Reverting now to the representative contents of the drawer 18 typified by the vertically disposed flat unfolded drawings, tracings, or blue 60 prints 12, Fig. 4 illustrates conventional examples of this type of vertical filing. As is well known in the art and as will be very briefly pointed out, the interior of the drawer is divided into a plurality of compartments disposed from front to rear of the drawer and defined by the spaces between two adjoining oppositely spring-pressed flexible strips 90 which hang vertically in the drawer on cross-wise hangers 91. There may be three or four pairs of these strips supported 65 by one of the hangers 91 and spaced apart cross-

wise of the drawer. The hanger also supports a center strip 92 between a pair of strips 90 and between the strips 90 are located coil springs 93 which press apart the strips 90 of the same hanger. Each of the hangers 91 may be of folded 5 formation to clamp the center strip 92 and two of the flexible strips 90 together at their tops while permitting the strips 90 to be pressed apart therebelow. While the strips 90 advantageously hang freely within the drawer except as influenced by the springs 93 and the drawings 12, the center strips themselves are preferably anchored to the bottom of the drawer as at 94.

For supporting the hangers 91, these may terminate at the sides of the drawer in flanges 15 95 which rest upon a ledge 96 which extends along the side of the drawer interior. Thereafter a plate 97 slotted as at 98 to pass over the hangers may be spot welded as at 99 to the drawer sides. The drawings 12 may be enclosed 20 by a large folder 12a of heavy paper or the like, for protection.

As best shown in Fig. 4, when reference is made to one of the drawings 12, the group of these drawings containing the one wanted is 25 pulled up and fanned out by dropping some of the drawings rearwardly and some forwardly as shown in dotted lines at 100 and 101, the drawing wanted being conveniently the then uppermost drawing in the group 101. It may not be 30 necessary in every case to remove the drawing entirely from the file, this being avoided whenever possible while still permitting observation of or reference to what the drawing contains. In such cases, the bail-like handle 84 may be 35 made to serve the function of a rest for the drawing cooperating with the drawer itself, when the drawings are in the fanned out position referred to. For this purpose the extensions 102 of the lower ends of the handle arms are extended beyond the trunnions 88 so that when the handle is inclined forwardly as shown in broken lines in Fig. 4, these extensions, as best 40 shown in Fig. 5, may be received in notches 103 in the rear wall of brackets 86 which cooperate 45 with the stop 104 extending between the bifurcations of the bracket, to support the handle in this position. An enlargement of the slots 87 laterally together with an inclined surface 105 in these slots permits the handle to be canted 50 into and out of inclined position, while being maintained in stable inclined position for supporting the drawings as mentioned.

For the purpose of providing ample clearance between the sides of the drawer and the casing 55 margin, the drawer sides 25 are desirably spaced inwardly from the outermost side edges 106 of the front face 27 of the drawer. This also permits the drawer to clear a bracket 80a carried on the inner side face of the casing to support 60 the air valve control member 80 at its forward end. The inwardly offset portion 107 which provides the ledge 96, also contributes still further to this necessary clearance for the moving parts.

Manifestly, the invention is not limited to details of construction described for purposes of illustration. Furthermore, it is not necessary that all features of the invention be used conjointly, as various combinations and sub- 70 combinations may be advantageously employed.

Having described my invention, I claim:

1. In filing means of the class described embodying heavy large size filing equipment, the combination with a drawer casing adapted to 75

- rest on the floor of an office or the like, of a relatively heavy large drawer received in said casing and adapted to be moved in and out thereof, and a permanent track co-planar with the floor of said casing projecting from said casing beneath said drawer in its withdrawn position wherein the drawer is operated by compressed air mechanism and carries a valve lever movable with the drawer for manually controlling said mechanism.
2. In filing means of the class described embodying heavy large size filing equipment, the combination with a drawer casing adapted to rest on the floor of an office or the like, of a relatively heavy large drawer received in said casing and adapted to be moved in and out thereof, and a permanent track co-planar with the floor of said casing projecting from said casing beneath said drawer in its withdrawn position wherein the drawer is operated by compressed air mechanism and carries a valve lever movable with the drawer for manually controlling said mechanism, and wherein the valve lever is connected with a pair of valve control members keyed to rotate together but relatively slideable longitudinally, one of which members is carried by the casing and the other of which is carried by the drawer.

3. In filing means of the class described, the combination of a casing, a drawer movable in the casing, a cylinder mounted on the casing, a piston therein connected with the drawer mechanism for admitting compressed air selectively to opposite ends of said cylinder for mechanically opening and closing the drawer, and a valve lever carried by and movable with the drawer for controlling said mechanism.

4. The structure of claim 3 wherein the casing carries a four-way valve controlled by said lever and air pipes communicate with opposite sides of said valve and with the opposite ends of said cylinder, and wherein telescoping members of non-circular cross-section respectively connect with said valve and said lever.

5. The structure of claim 3 wherein the casing carries a four-way valve controlled by said lever and air pipes communicate with opposite sides of said valve and with the opposite ends of said cylinder, wherein said valve has an inlet duct and an outlet duct oppositely disposed between said pipes, and wherein needle valves control the passage through said ducts, said needle valves being connected with adjustment rods carried by the front of the casing.

HAROLD L. DE LISLE.
